UNITED STATES PATENT OFFICE.

ARNO BÖTTNER, OF SUDENBURG, NEAR MAGDEBURG, GERMANY, ASSIGNOR TO THE FIRM: POLTE, OF MAGDEBURG, GERMANY.

DEVICE FOR OPERATING GATE VALVES.

Application filed December 27, 1924. Serial No. 758,378.

To all whom it may concern:

Be it known that I, ARNO BÖTTNER, a citizen of the German Republic, residing at 58 Helmstederstrasse, Sudenburg, near Magdeburg, Germany, have invented certain new and useful Improvements in Devices for Operating Gate Valves, of which the following is a specification.

My invention relates to an improved device or means for operating a gate valve of the type comprising a body or gate composed of a plurality of cut-off plates adapted to be moved vertically and laterally towards and from the co-acting packing faces, and a threaded spindle adapted to be coupled, for the purpose of accomplishing the said lateral movements, with its nut temporarily by means of a claw or nose coupling and to be uncoupled therefrom by means of lifting rods or pins.

The object of my invention is to provide an operating device of the stated kind which is of simple construction so as to ensure prompt, effective and reliable operation.

With this object in view I mount and arrange the stated lifting rods or pins in a manner that the top ends thereof will immediately act upon the coupling member to disengage the same, at the right moment, from the nut when, on turning the handle of the nut, the rods are caused to ascend onto the summits of noses or tappets of a cam I provide for the purpose below the nut.

In the accompanying drawings, forming a part of this specification and showing for purposes of exemplification a preferred form and manner in which my invention may be embodied and practiced, Figure 1 is a sectional view and Figure 2 is an elevation of the operating device with the spindle and the nut or its handle coupled together; and Figure 3 is a similar view as Figure 2 with the parts uncoupled and the spindle in an upper position.

The slide or valve body properly speaking and the valve case are not shown in the drawings since they are of conventional construction. Parts which are repeated in the several figures bear the same reference characters in each case.

The spindle α carries a nut g forming the hub portion of a hand-wheel b , as usual, and to the lower end of the spindle the slide or valve body (not shown) is attached in the usual manner so that description thereof is

unnecessary. Rigidly connected with the upper end of the spindle α is a head c having a short cylinder or sleeve d , fitted thereon to be freely displaceable in the direction of its axis but rotatable therewith, a coiled spring e being inserted into the annular space between the inner face of the sleeve d and the outer face of the head c so as to bear against the enlarged bottom portion d^1 of the sleeve d . The other end of the spring bears against a cap nut h loosely fitted in the sleeve and screwed onto the upper extremity of the spindle α , whereby any movements of the sleeve d in the direction of the axis of the spindle will be controlled by the spring e . It will be seen that the sleeve d is thus yieldingly supported by the head c and the cap nut h , and that the action of the spring e can be adjusted by means of the cap nut h .

The enlarged bottom end d^1 of the sleeve d is provided with two diametrically opposed claws or lugs f projecting therefrom in a direction parallel to the axis of the spindle α in order to engage in two corresponding recesses g^1 cut in the upper face of the nut g . The nut or hub portion of the hand wheel b is bored at two diametrically opposed points in the direction of the axis of the spindle α for the reception of two pins h adapted to slide in the bores and normally lying with their upper end faces flush with the bottom faces of the grooves or recesses g^1 , while the lower ends of the pins h bear against or rest upon a stationary cam i provided in a horizontal plane below that of the hand wheel b and having two curved tappets or noses i^1 located diametrically opposed to each other in the path of the pins h , the arrangement being such that when the pins h ascend and reach the summit of the tappets, the lugs f will be out of engagement with the recesses g^1 .

The operation of the device is as follows:

At the up and down movements of the slide or valve body on turning the hand wheel b in the one or the other direction, the spindle α performs rectilinear movements only in vertical direction, stops being usually provided within the valve case for preventing the spindle from rotation, as will be known to persons versed in the art, so that a description thereof is not deemed necessary.

Supposing the slide or valve body is

operated for closing the valve, then the head *c* will come in contact with the nut or hub of the hand wheel, while at the same time the slide or valve body has reached its abutment at the bottom of the case and the spindle has disengaged from the said stops, the coupling lugs or noses *f* engaging at that time in the recesses *g*¹ of the nut or hub. The spindle *a* thus is coupled with the 10 nut *g* so as to rotate therewith as the hand-wheel *b* is further rotated whereby the cut-off plates forming the valve body are forced in a known manner towards and onto their seats. During such rotation the pins *h* provided in the nut or hub of the hand-wheel slide over or on the cam *i* without being lifted by the latter.

In case of opening the valve the hand-wheel *b* and consequently also the spindle *a* still coupled with the wheel or the nut forming a part of the wheel, are turned in the opposite direction until the pins *h* have reached the summits of the tappets *i*¹, whereby the cut-off plates are disengaged from their seats. In the upper or elevated position shown in Figure 3 the pins *h* enter into the recesses *g*¹ in order to disengage and lift therefrom the lugs or noses *f* and the sleeve *d* integral therewith, against the action of the coiled spring *e*, whereby the coupling of the spindle with the nut or the hand-wheel integral therewith, will be disconnected. In the meantime the spindle is again arrested by the hereinbefore stated stops in the case 35 whereby, on a continued rotation of the hand-wheel, the spindle will be axially displaced in upward direction and the cut-off plates of the valve will be carried along owing to their firm connection with the spindle.

The perpendicular length of the coupling lugs or noses *f* which project downwards from or beyond the bottom face of the abutting head *c* attached to the upper end of the spindle *a*, is preferably equal to half the 45 pitch of the spindle.

In operating the described device approximately one half revolution of the hand-wheel only is required for closing or for 50 opening the valve, whereas in the governing device hitherto used or suggested for controlling a valve of the type a full revolution or even several revolutions are required for the like purpose.

From the foregoing description it will be seen that simple and efficient means are herein provided for accomplishing the object of my invention, but while the elements shown and described are well adapted to 55 serve the purposes for which they are intended, it is to be understood, that the invention is not limited to the precise construction set forth, but includes within its purview such changes as may be made within the scope of the appended claims.

What I claim is:—

1. A valve operating device of the character set forth comprising a threaded spindle, a nut engaging said spindle to co-operate therewith and having recesses therein, a hand-wheel rigidly connected with the said nut, a sleeve on the end of said spindle and having lugs thereon which are adapted to cooperate with said recesses, lifting pins adapted to disconnect the lugs from the recesses, and a stationary cam cooperating with the said pins, substantially as and for the purpose set forth. 75

2. A valve operating device of the character set forth, comprising a threaded spindle, a nut engaging said spindle to co-operate therewith and having recesses therein, a hand-wheel rigidly connected with the said nut, a sleeve resiliently mounted on the top of the said sleeve and having lugs thereon which are adapted to cooperate with said recesses, pins slidably mounted in the nut, and a stationary cam mounted below the nut and adapted for co-operation with the said pins, substantially as and for the purpose 80 set forth. 85

3. A valve operating device comprising a threaded spindle; a wheel and hub in threaded engagement with and adapted to operate said spindle, said hub having recesses therein; a spring pressed sleeve on the end of said spindle having lugs thereon which are adapted to engage in said recesses; and means for disconnecting the lugs from the recesses in order that a rotation of the wheel 95 will change a rotary movement of the spindle to a vertical movement. 100

4. A valve operating device comprising a threaded spindle; a wheel and hub in threaded engagement with and adapted to operate said spindle; a sleeve on the end of said spindle, said hub and sleeve being provided with lugs and recesses which are adapted to engage in each other; and means associated with said hub for disconnecting the lugs 105 from the recesses in order that a rotation of the wheel will change a rotary movement of the spindle to a vertical movement. 110

5. A valve operating device comprising a threaded spindle; a hub in threaded engagement with the spindle for vertically moving said spindle upon rotation of the hub to lower the valve; a sleeve on the spindle; and means for causing engagement between the hub and sleeve to rotate the spindle. 115

6. A valve operating device comprising a screw threaded spindle and a handle therefor; a hub for said handle having internal screw-threads which are adapted to engage said spindle and having recesses therein; a spring pressed sleeve on the end of said spindle having lugs thereon which are adapted to engage in said recesses; a plurality of cams associated with said hub; and a plurality of pins in said hub for disconnecting 125 130

the lugs from the recess when actuated by said cams in order that a rotation of the wheel will change a rotary movement of the spindle to a vertical movement.

- 5 7. A valve operating device comprising a screw threaded spindle and a handle therefor; a hub for said handle having internal screw-threads which are adapted to engage said spindle and having recesses therein; a 10 spring pressed sleeve on the end of said spindle having lugs thereon which are adapted to engage in said recesses; a cam associated with said hub; and a plurality of pins in said hub adapted to cooperate with 15 said cam for disconnecting the lugs from the recess in order that a rotation of the wheel will change a rotary movement of the spindle to a vertical movement.

8. A valve operating device comprising a 20 threaded spindle; a wheel and threaded hub

for engaging and operating said spindle, said hub having recesses therein; a sleeve on the end of said spindle having lugs thereon which are adapted to engage in said recesses; and means for disconnecting the lugs from 25 the recesses in order that a rotation of the wheel will change a rotary movement of the spindle to a vertical movement.

9. A valve operating device comprising a 30 threaded spindle; a hub in threaded engagement with the spindle for vertically moving said spindle upon rotation of the hub to lower the valve; and a sleeve on the end of the spindle which is adapted to engage the hub when the spindle reaches its lowest position in order to rotate the spindle upon 35 rotation of the hub.

In testimony whereof I affix my signature.

ARNO BÖTTNER.
